Primary Examiner — Lauren D McVey*Assistant Examiner* — Elisa Maria Pujals(74) *Attorney, Agent, or Firm* — Daniel M. Cohn; Howard M. Cohn(57) **CLAIM**

The ornamental design for an electronic toy, as shown and described.

DESCRIPTION

FIG. 1 is a perspective view of an electronic toy showing my new design;

FIG. 2 is another perspective view thereof;

FIG. 3 is a front elevation view thereof;

FIG. 4 is a rear elevation view thereof;

FIG. 5 is a left-side elevation view thereof;

FIG. 6 is a right-side elevation view thereof;

FIG. 7 is a top plan view thereof;

FIG. 8 is bottom plan view thereof;

FIG. 9 is an enlarged view of the encircled portion in FIG. 1; and,

FIG. 10 is an enlarged view of the encircled portion in FIG. 2.

The evenly spaced broken lines depict portions of the article that form no part of the claimed design. The dot-dash broken lines indicating enlargement portion of the design form no part of the claimed design.

1 Claim, 10 Drawing Sheets(56)
